ABSTRACT: A filler for use with a carton filling machine having an improved no carton-no fill mechanism arranged such that the capacity of the volumetric filling mechanism thereof can be changed without making a number of additional adjustments. Also, the hopper and the cup support for the filler is adapted to be vibrated, to provide improved carton fill.

CARTON FILLER

This invention relates, generally, to improved carton filling machines and, more particularly, to an improved filler for carton filling machines.

An object of the invention is to provide an improved filler for carton filling machines including means for maintaining the net weight contents of the filled cartons within closer limits than heretofore generally possible.

Another object is to provide an improved filler for carton filling machines constructed in a fashion such that it can be more easily and more quickly adjusted to vary the volume of the volumetric filling mechanism thereof.

Still another object is to provide an improved filler for carton filling machines capable of continuous operation at high speeds, and constructed in a fashion such that it can be operated with a minimum of maintenance.

A further object is to provide an improved filler having a no carton-no fill mechanism which is operative to prevent the product from being deposited in the volumetric filling mechanism, in the absence of a carton or cartons.

Still another object is to provide an improved filler for carton filling machines having a construction such that the product is caused to drop a greater distance into the cartons, so that the latter are filled and packed more compactly without the need of additional packing mechanisms.

Other objects of the invention will in part be obvious and will in part appear hereinafter.

The invention accordingly comprises the features of construction, combination of elements, and arrangement of parts which will be exemplified in the construction hereinafter set forth, and the scope of the invention will be indicated in the claims.

For a fuller understanding of the nature and objects of the invention, reference should be had to the following detailed description taken in connection with the accompanying drawings in which:

FIG. 1 is a top plan view of a filler exemplary of the present invention;

FIG. 2 is a sectional view of the filler of FIG. 1, taken substantially transversely through it;

FIG. 3 is a partial top plan view of the filler of FIG. 1, partially broken away so that the construction and operation of the no carton-no fill arm thereof can be more easily shown and described, the same being operated to open each of the cutoff gates of the filler;

FIG. 4 is a view similar to FIG. 3, however, illustrating the no carton-no fill arm in its operative position for closing the cutoff gates of the filler;

FIG. 5 is a top plan view of the top cup and cutoff plate carrier of the filler;

FIG. 6 is a sectional view, taken substantially along line 6-6 of FIG. 5;

FIG. 7 is a sectional view, taken substantially along line 7-7 of FIG. 5;

FIG. 8 is a top plan view of the lower cup support plate of the filler;

FIG. 9 is a sectional view taken substantially along line 9-9 of FIG. 8;

FIG. 10 is a partial sectional view, taken substantially along lines 10-10 of FIG. 8;

FIG. 11 is a partial side plan view of the lower cup support plate of FIG. 8, illustrating the locking slot formed therein;

FIG. 12 is a top plan view of the cutoff plate of the filler;

FIG. 13 is a sectional view taken substantially along lines 13-13 of FIG. 12;

FIG. 14 is a top plan view of the funnel ring of the filler; and

FIG. 15 is a sectional view taken substantially along lines 15-15 of FIG. 14.

Similar reference characters refer to similar parts throughout the several views of the drawings.

Referring now to the drawings, particularly FIGS. 1 and 2 thereof, there is illustrated a filler 10 which is well suited for filling cartons with a whole host of different type materials such as, for example, corn, peas, beans, to mention but a few

of them. Of particular importance is the fact that the filler is easily adaptable for use with most presently available rotary carton filling machines so that the latter can be easily modified and improved. One such type of machine is disclosed in U.S. Pat. No. 2,910,212 to Charles E. Kerr.

The filler 10, as can be best seen in FIG. 2, includes a main shaft 20 which is fixed against rotation and which is adapted to be raised or lowered to increase or decrease the net weight of the material deposited in the cartons, by changing the capacity of the pockets or cups 18 which form the volumetric filling mechanism of the filler 10, in a manner fully described below. The manner in which this main shaft 20 is fixed and is raised or lowered can be as disclosed in the above-mentioned U.S. Pat. No. 2,910,212.

15 Affixed to the upper end of the main shaft 20 and secured against rotation thereon is a no carton-no fill arm 110. The upper end of the main shaft 20 is press-fitted into a tapered bore 112 of a hub 111 on the one end of the no carton-no fill arm 110, and is retained therein by means of a threaded bolt 113 and a washer 114.

20 The no carton-no fill arm 110 is generally T-shaped in cross section, and it is supported on the main shaft 20 such that the stem 115 of the T is horizontally disposed and the crossbar 116 thereof is vertically disposed. A double acting hydraulic cylinder 118 which can be a Bimba 091-DP cylinder is affixed to a flange 119 integrally formed with the stem 115 of the arm 110 and to one end of a lever arm 120 so as to lie parallel to the arm 110. The lever arm 120 is pivotally affixed by means 25 of a pivot bolt 121 to the arm 110, and its opposite end has one end of a connecting rod 122 pivotally affixed to it. An adjustment rod 123 which can be lengthened or shortened is pivotally affixed at one of its ends to the lever arm 120, between the end thereof to which the hydraulic cylinder 118 is affixed and the pivot bolt 121. The opposite end of the adjustment rod 123 is fixedly and pivotally secured to one end of a shorter lever arm 124 which is pivotally affixed at its other end to the arm 110, by means of a pivot bolt 125. The lever arms 120 and 124 are affixed to and positionably adjust a pair of 30 cam bars 58 and 59, respectively, which are positioned below the arm 110 so as to be engaged by a cam roller 57 to open and close cutoff gates 56, in a manner and for reasons described more fully below. The opposite end of the connecting rod 122 is pivotally affixed to one end of a lever arm 126 which is affixed to and positionably adjusts a product flow gate 127.

35 A hub 21 of an annular hopper plate 22 is loosely fitted onto the upper end of the main shaft 20, substantially immediately below the hub 111 of the no carton-no fill arm 110. The hopper plate 22 has an opening in it, in which is affixed the lower edge of a hopper 11. Means not shown are adapted to convey a product to the hopper 11 so that the latter generally is maintained full during carton filling operations, in any well-known manner. A number of other openings 23 (three as illustrated) can be provided in the hopper plate 22, for viewing the product dropped through the hopper 11 onto a top cup and cutoff plate carrier 24.

40 The top cup and cutoff plate carrier 24, hereinafter generally referred to as the carrier 24, is rotatably supported on the main shaft 20 by means of a carrier hub 26 which, in turn, supports a pair of bearings 27 and 28. The bearing 28 seats on a shoulder 29 on the carrier hub 26, and the bearing 27 is retained in spaced relation from the bearing 28 by an annular projecting shoulder 30 formed on a hub portion 38 of the carrier 24. A snap ring 31 is provided to retain the bearings 27 and 28 in proper position with respect to the carrier hub 26 and the hub portion 38 of the carrier 24. The carrier hub 26 further is positionably retained on the main shaft 20, by means of a thrust washer 32 and a snap ring 33.

45 It may be noted that a pair of resilient O-rings 34 and 35 are sandwiched between the hubs 111 and 21 and between the carrier hub 26 and the washer 32, respectively. These O-rings 34 and 35 are provided to permit the hopper plate 22 and the carrier 24 to be vibrated during the carton filling operation, by

means of a vibrator 12 affixed to the hopper plate 22, adjacent to the hopper 11. The vibrator 12 can be a KOIAC Cleveland Vibrator which is hydraulically operated and which has been found to be entirely satisfactory for the intended application. With this construction, it is found that the vibratory motion imparted to the hopper plate 22 and to the carrier 24 causes more even product flow from the hopper 11 so that there is less tendency for the product to stick in the hopper and, more importantly, so that the cups 18 comprising the volumetric filling mechanism of the filling machine 10 fill more evenly or uniformly. As a result of this latter feature, it is found that the net weight contents of the filled cartons can be more closely controlled, to thereby substantially reduce the cost of the product used in filling the cartons, by eliminating the need for overfilling to assure that minimum weight requirements are met.

The carrier 24 has an upstanding flange 36 extending about its peripheral, near its outer edge, which together with the hub portion 38 forms an annular pocket 37 into which the product from the hopper 11 drops. The upper end of the flange 36 is closely spaced to the outer peripheral edge of the hopper plate 22 so as to effectively seal the pocket 37 to prevent any product from spilling out of it. An annular resilient hopper seal 39 also is secured between the outermost top edge of the hub portion 38 and the hopper plate 22, for retaining material within the pocket 37.

The carrier 24 also has a number of cup openings 40 (12 as illustrated) formed in it adjacent its outer edge, in radially spaced relation. A shorter flange 41 extends downwardly from the underside of the carrier 24 about each of these cup openings 40, and a tubular top cup 42, which comprises a part of a cup 18 of the volumetric filling mechanism, is secured therein. A cutoff gate arm 44 formed of a shaft portion 46 having one end of a cam roller support arm 47 integrally affixed to its upper end is associated with each of the cup openings 40. The shaft portions 46 of the cutoff gate arms 44 are extended through an enlarged bore 48 and an axially aligned shaft aperture 49 formed in the flange 36 of the carrier 24, and secured therein by means of a jam nut 50. A spring 51 encircling the shaft portion 46 is retained within the bore 48 by a bushing 52 having an enlarged head portion 53 which seats on the top edge of the flange 36 and bears against the underside of the cam roller support arm 47. The flange 36 has slots 55 formed in it, positionally aligned with each of the cup openings 40, for slidably receiving therein cutoff gates 56 which are affixed to the shaft portions 46 of the cutoff gate arms 44 and operated by the latter to close the cup openings 40 in the manner described more fully below. These cutoff gates 56, as can be best seen in FIGS. 3 and 4, are thin, flat, generally tear-shaped plates of sufficient size to completely close the cup openings 40. A cam roller 57 is rotatably and fixedly secured to the free end of each of the cam roller support arms 47, and is positioned to engage one or the other of the above-mentioned cam bars 58 and 59 to pivot the cutoff gates 56 to open and close the cup openings 40, in the manner described more fully below.

Beneath the carrier 24 is a lower cup support plate 132, which is supported by a cutoff plate 140 described below. The lower cup support plate 132, as can be best seen in FIGS. 2 and 8-11, is in the form of an annular ring and has openings 133 corresponding in number to and aligned with the openings 40 formed in the carrier 24 in it. These openings 133 have upstanding annular flanges 134 formed about them, in which are secured a lower cup 135. These lower cups 135 are slightly larger in diameter than the top cup 42, and the latter are slidably telescopically received therein. A number of flanges 136 (three as illustrated) are integrally formed with the lower cup support plate 132 and extend radially outwardly a short length beyond the peripheral edge thereof. The flanges 136 each have locking slots 137 formed in them, for receiving drive bars 61 for lockingly and drivingly coupling the lower cup support plate 132 to the carrier 24 and a funnel ring 60 (described below) so that these elements all rotate together, in a manner described more fully below.

The cutoff plate 140, as can be best seen in FIGS. 2, 12 and 13 is in the form of a circular plate and has a hub 141 with a tapered bore 142 in it, for receiving, in a press-fit fashion, the upper end of an elongated housing 70. The housing 70, and hence the cutoff plate 140, is fixed against rotation. The housing 70 further has a bore 71 for receiving the main shaft 20 therethrough, and its lower end is adapted to be affixed to a support surface (not shown) on the carton filling machine, to support the carton filler 10. An arcuate opening 143 which defines a carton filling position and which is of a size such that three of the openings 133 in the lower cup support plate 132 simultaneously overlap it is formed in the cutoff plate 140. This arcuate opening 143 is the only opening through which the product can drop into the cartons to fill them, as described more fully below. The cutoff plate 140 further has a recessed annular groove 144 in it, in which the lower cup support plate 132 rides.

The funnel ring 60 having a hub portion 66 is rotatably supported, by means of bearings 67 and 68, upon the housing 70, below the cutoff plate 140. This funnel ring 60 has a flat funnel support surface 72 which extends parallel to the carrier 24 and is coupled to a hub portion 66 by means of tapered spokes 73. The funnel support surface 72 has funnel openings 74 corresponding in number to and positionally aligned with the openings 40 in the carrier 24 formed in it. A number of flanges 65 (three as illustrated) which extend radially outwardly from the peripheral edge of the funnel ring 60 and which have locking slots 64 formed in them, are integrally formed on the funnel ring. Drive bars 61 in the form of lengths of rectangular-shaped bar stock are removably fixedly secured within the slots 62 in the carrier 24, by means of threaded bolts 63, and are slidably received within the locking slots 137 of the lower cup support plate 132 and the locking slots 64 of the funnel ring 60. These drive bars 61, as indicated above, lockingly and drivingly couple these three elements together so that they all rotate simultaneously together. In addition, this arrangement permits the main shaft 20 to be raised and lowered to change the capacity of the pockets or cup 18 to thereby change the volumetric capacity of the product dropped in the cartons, without the necessity of removing any fastening means such as threaded bolts or the like or the necessity of adjustably positioning the no carton-no fill mechanism, as is generally required in the case of most existing similar filling machines. Accordingly, the volumetric capacity of the filler 10 can be easily and quickly adjusted, merely by raising and lowering the main shaft 20, and there is no lost down time of the filling machine, while this adjustment is made.

Beneath each of the openings 74 in the funnel ring 60 is a rigid funnel 75 having four walls, two of which are tapered so as to form a large, generally rectangular-shaped open top 76 which completely surrounds an opening 74 and a narrower, generally rectangular-shaped outlet 78. The funnel ring 60 also has a funnel slide bar 79 associated with each of the openings 74, and the funnel slide bars are fixedly secured within openings 80 formed in flanges 81 depending from the upper side of the funnel ring 60. These funnel slide bars 79 each support a bracket 85 which, in turn, supports a funnel extension 82. These funnel extensions 82 are generally shaped like the rigid funnels 75, and each includes a fixed portion 83 and a pivotal portion 84.

A roller 87 is affixed to the rear wall 88 of each of the brackets 85, and these rollers 87 all ride in an annular funnel cam track 89 formed on the end of an arm 86 integrally formed with and extending from the housing 70. This funnel cam track 89 is curved so that the brackets 85, and hence the funnel extensions 82, are raised and lowered as the funnel ring 60 is rotated. The arrangement or curvature is such that the ends of the funnel extensions 82 are lowered into the open tops of the cartons for a preestablished arc of rotation to fill a carton, as described more fully below.

The pivotal portions 84 of the funnel extensions 82 are pivotally affixed to the brackets 85 by means of pivot pins 90 and pivot flanges 91 affixed to the rear walls 92 thereof. A roller 93 also is affixed to the rear walls 92, and these rollers

are adapted to ride on a cam rail 94 affixed by means of a thread bolt 95 to the funnel slide bars 79. The cam rails 94 each have an angularly disposed cam surface 96 on them which is flanked by two flat cam surfaces 97 and 98. In FIG. 2, the bracket 85, and hence the funnel extension 82, are in their lowered positions, and it can be seen that the roller 93 is on the flat cam surface 98 and the mouth of the funnel extension is opened so that the edges thereof just engage but do not bow the sidewalls of the carton 100. As the bracket 85 is raised, by the roller 87 rolling in the cam truck 89, the roller 93 on the pivotal portion 84 of the funnel extension 82 rolls down the angularly disposed cam surface 96 and onto the flat cam surface 97. When on this latter cam surface, the end of the pivotal portion is pivoted so as to substantially close the mouth of the funnel extension 82, to permit the ends or the mouth thereof to be more easily lowered into a carton.

The funnel slide bars 79 each have an outwardly projecting flange 102 on each of the opposite sides of the main body portion 103 thereof. These flanges 102 function to separate and to guide rollers 104 affixed to the brackets 85, to align and to guide the funnel extensions 82 as they are raised and lowered. A number (three in the illustrated example) of the funnel slide bars 79 are longer in length than the others, and these longer funnel slide bars are adapted to be driven, to rotatably drive the funnel ring 60 in synchronism with the feed speed of the filling machine to which the filler machine 10 is affixed. In the illustrated embodiment, these funnel slide bars 79 are adapted to be engaged by one of the brackets 145 which are affixed on top of the chain sprocket for a conveyor chain 146 which is adapted to retain the cartons to be filled and to deliver them to the filler machine 10. This apparatus and method for feeding or conveying cartons is well known in the art and forms no part of the present invention. With this drive arrangement, it can be seen that the possibility of the filler machine 10 becoming unsynchronized with the cartons being fed to it for filling is virtually impossible. The carrier 24 and the lower cup support plate 132 are, in turn, rotated by the funnel ring 60 as the latter is rotated, since they all are coupled to one another by the drive bars 61.

The vibrator 12 and the hydraulic cylinder 118 controlling the operation of the no carton-no fill arm 110 are operated by means of a valve mechanism 17. This valve mechanism 17 is arranged to continuously operate the vibrator 12 when the filling machine to which the filler machine 10 is affixed is being operated, so that the hopper plate 22, the hopper 11 and the carrier 24 are constantly vibrated. The hydraulic cylinder 118 is operated by the valve mechanism 17, in response to the operation of a no carton detecting mechanism such as the microswitch 150. This microswitch 150 is placed at a predetermined location, in the path of the cartons being conveyed to the filler 10 in a fashion such that the leaf switch 151 thereof is engaged and operated by the cartons, in the following manner. As long as the leaf switch 151 is engaged and operated by a carton, the microswitch 150 operates the valve mechanism 17 which, in turn, operates the hydraulic cylinder 118 so that the cam bars 58 and 59 are pivotally positioned to cause the cam roller 57 to be engaged by the cam bar 59. As illustrated in FIG. 3, the cam bars 58 and 59 have been pivoted in the described manner and it can be seen that the cutoff gate 56 is already in its open position so that its associated cam roller 57 freely passes between the two cam bars 58 and 59. The next cutoff gate 56', however, is in its closed position and its associated cam roller 57' will engage the cam surface of the cam bar 59 as the carrier 24 is rotated in a clockwise direction. As the cam roller 57' moves along the cam surface of the cam bar 59, the cam roller support arm 47' is caused to pivot which action, in turn, causes the cutoff gate 56' to pivot to its open position. Accordingly, as long as there is a continuous flow of cartons over the microswitch 150, the cam bars 58 and 59 will be in the position illustrated in FIG. 3 and all of the cam rollers 57 and hence the cutoff gates 56 will be pivoted such that the cutoff gates 56 are in their open positions.

If there is an absence of a carton or cartons in the stream of cartons being fed to the filler 10, the microswitch 150 is operated to cause the valve mechanism 17 to, in turn, operate the hydraulic cylinder 118 of the no carton-no fill arm 110 to pivot the cam bars 58 and 59 to the position illustrated in FIG. 4. In the figure, it can be seen that the cutoff gate 56 is in its open position and, as the carrier 24 continues to rotate in a clockwise direction, its associated cam roller 57 will engage the cam surface of the cam bar 58. As the cam roller 57 moves along this cam surface, the cam roller support arm 47 is caused to pivot in a counterclockwise direction which action, in turn, causes the cutoff gate 56 to swing to its closed position. This can be seen more clearly by referring to the cam roller 57' which, as illustrated, is about to pass free of the cam bar 58 so that it already has caused its associated cam lever support arm 47' to be pivoted to close the cutoff gate 56'.

The microswitch 150 is positioned so that it is triggered by a missing carton to operate the no carton-no fill arm 110, in the manner described above, to close only the cutoff gate 56 of the cup 18 which normally would contain the product to be dropped into that missing carton when the latter arrives at the carton fill position. Since the cutoff gate 56 is closed as the cup 18 associated with the missing carton passes beneath the hopper 11, no product is permitted to drop into it. In most presently available similar types of filler machines, the cup is filled with the product and the no carton-no fill mechanism is operated by a missing carton to prevent the product from being spilled out of the cup. This arrangement is generally found to be unsatisfactory, particularly when the cartons are being filled with products such as frozen corn or peas, since this type of product tends to set up or freeze to the sidewalls of the cups during the time that it is retained within the cup and dropped into a carton, usually during the next revolution of the cup carrier. If some of the product sticks to the sidewalls of the cups, it is obvious that the carton will not have the correct net weight of product deposited in it. Accordingly, this problem is virtually eliminated with the arrangement of the present invention. The next carton following the missing carton immediately triggers the microswitch 150 to operate the no carton-no fill arm 110 to prevent the cutoff gate 56 of the cup 18 synchronized with that carton from being closed.

It may also be noted that the connecting rod 122 also is operated by the lever arm 120. The operation is such that it operates the lever arm 126 to cause it to pivot to, in turn, pivot the product flow gate 127 to substantially cut off the flow of product from the hopper 11, each time the no carton-no fill arm 110 is operated by a missing carton. The product flow gate 127 functions to prevent an overfill of product to flow into the carrier 24, to thereby prevent the latter from being clogged with too much product. Wiper brushes 155, three as illustrated, are affixed to the underside of the hopper plate 22 to sweep the product spilling from the hopper 11 into the carrier 24 to the outer periphery of the latter and into the cups 18. These wiper brushes 155 also function to sweep off any overfill in a cup 18, to assure that all cups 18 are filled flush to their tops.

Now that the construction of the filler 10 has been described, its operation can be described as follows. As indicated above, the product to be deposited in the cartons 100 is conveyed and spilled into the hopper 11, in any suitable fashion. The filling machine to which the filler 10 is affixed is energized and the cartons 100 normally are supplied to it in a knock-down fashion, the same being erected and the lower ends thereof closed as they are conveyed along the length of the filling machine, by a mechanism well known and not forming part of the present invention, to the filler 10. In the illustrated example, these cartons are conveyed to the filler 10, by means of the chain belt 146. The brackets 145 on the chain sprocket engage the longer ones of the funnel slide bars 79 to thereby rotate the funnel ring 60, and hence the carrier 24 and the lower cup support plate 132, which are coupled to the funnel ring 60 by means of the drive bars 61. As indicated above, the housing 70 supporting the cam track 89 and the cutoff

plate 140 supported by it both are fixed against rotation. The hopper plate 22 and the no carton-no fill arm 110 affixed to and supported by the main shaft 20 likewise are fixed against rotation.

The product spilled into the hopper 11 drops through it into the pocket 37 in the carrier 24, and as the latter rotates, the product in the pocket 37 is swept by the wiper brushes 155 towards the outer periphery of the carrier 24 and into the cups 18, through the openings 40 and the carrier 24. The operation of the chain belt 146 conveying the cartons 100 to the filler 10 and the operation of the filler 10 are synchronized so that funnel extensions 82 start to drop into the open top of the cartons 100, just prior to the time that the cups 18 pass over the carton fill position defined by the arcuate slot 143 formed in the cutoff plate 140.

The funnel extension 82 are raised and lowered by means of the roller 87 affixed to the bracket 85 and retained within the cam track 89. As the funnel extension 82 is lowered, its lower end is closed so that the end can be more easily inserted into the open top of the carton. As the roller 93 affixed to the rear wall 92 of the pivotal position 84 of the funnel extension 82 is rolled down the cam rail 94, by the movement of the bracket 85 due to the roller 87 following the path of the cam track 89, the pivotal portion 84 is pivotally moved to open the end of the funnel extension 82, to permit the product to drop through it into the carton 100. The funnel extension 82 will be at its lowermost point at the time that its associated cup 18 starts to pass over the arcuate opening 143 in the cutoff plate 140. At this time, the product is permitted to spill out of the cup 18 and through the funnel 75 and the funnel extension 82 in the carton 100. It may be noted that the funnel 75 and the funnel extension 82 are of a substantial length so that the product is caused to fall a considerable distance from the cup 18 into the carton 100. It is found that by causing the product to drop a substantial height, as in the illustrated case, the product is more compactly packed within the carton 100 and that the need for additional packing mechanisms for packing the product so that the top flaps of the cartons can thereafter be easily closed is eliminated. Also, this long drop eliminates the need to bow the sidewalls of the cartons to assure that all of the product in the cups can be retained within the carton, as has been done in the past, is eliminated. This type of operation, that is, bowing of the sidewalls of the cartons, is generally objected to since the cartons are sometimes damaged by this operation and, furthermore, additional equipment usually is necessary to flatten the cartons after they are filled so that the sides thereof do not appear to bulge. The funnel extensions 82 preferably remain within the cartons 100 during the time that the cups 18 are over the arcuate opening 143 formed in the cutoff plate 140. The length of the arcuate opening 143 is sufficient to assure that all of the product within the cups 18 are spilled therefrom into the cartons. As indicated above, the hopper plate 22 has a vibrator 12 affixed to it which constantly vibrates the hopper plate 22, the hopper 11 and the carrier 24 to assure a continuous flow of product through the hopper 11 and, more importantly, to assure that each of the cups 18 comprising the volumetric measuring mechanism of the filler 10 are more uniformly filled as they pass beneath the hopper 11. As indicated above, this feature permits the net weight contents of the cartons to be controlled within closer limits than heretofore generally possible. The vibratory motion of the carrier 24, of course, also functions to prevent the product from sticking to the sidewalls of the top cups 42 forming a part of the cups 18 so that all of the product within the cups 18 drops out of it during virtually every operation. This factor therefore likewise contributes to the ability to maintain the net weight contents of the cartons within closer limits.

If during the operation of the filling machine, a carton is missing in the line of continuous cartons being fed to the filler 10, the microswitch 150 is triggered to operate the valve mechanism 17 to, in turn, operate the hydraulic cylinder 118 of the no carton-no fill arm 110. The hydraulic cylinder 118, in operating, operates the lever arm 120 to pivot the cam bars

58 and 59 to the position illustrated in FIG. 4. In this position, the cam roller 57 affixed to the cam roller support arm 47 of the cutoff gate 56 controlling the flow of product into the cup 18 which would contain the product to be deposited in the 10 carton which is missing in the line of cartons being conveyed to the filler 10 engages the cam bar 58. This action causes the cam roller support arm 47 to pivot, in the manner described above, to close the cutoff gate 56 so that the cup 18 does not fill with the product as it passes beneath the hopper 11. Also, 15 at the same time that the cutoff gate 56 is being closed, the produced flow gate 127 is pivoted to cut off the flow of product from the hopper 11. The carton following the missing carton again trips the microswitch 150 so that the latter operates the valve mechanism 17 to, in turn, operate the hydraulic cylinder 118 to again position the cam bars 58 and 59, in the positions illustrated in FIG. 3. The cutoff gate 56 which was closed by the cam bar 58 remains closed during one 20 revolution of the carrier 24 and is subsequently again opened by the cam bar 59, in the manner described above, if at this time there is a carton in the line of cartons synchronized with its movement. Since the product is prevented from filling a cup 18 if there is no carton into which this product can be spilled when that cup reaches the arcuate opening 143 in the 25 cutoff plate 140, the product is prevented from setting up or freezing in this pocket during the next revolution before it can be spilled from it. Therefore, the problem of these cups becoming clogged as a result of the product freezing to the sidewalls thereof and the problem of having less than the 30 necessary net weight of product being spilled into a carton as a result of some of the product sticking within the cups is substantially, if not completely eliminated.

If it is desired to change the capacity of the volumetric measuring mechanism of the filler 10, that is, the capacity of the 35 cups 18, this can be easily and quickly accomplished merely by raising or lowering the main shaft 20. In doing so, the carrier 24, the hopper plate 22 and the no carton-no fill arm 110 all are simultaneously raised or lowered with respect to the funnel ring 60, the cutoff plate 140 and the lower cup support plate 132. The driving connection between the funnel ring 60, the lower cup support plate 132 and the carrier 24 is maintained since the drive bars 61 merely slide upwardly or downwardly within the locking slots formed in these members. The top cups 42 affixed to the carrier 24 are slidably and telescopically retained within the lower cups 135 affixed to the lower cup support plate 132, hence it can be seen that the volume of the cups 18 is changed as the carrier 24 is raised or lowered. With this arrangement, it can be seen that the 45 volume or capacity of the cups 18 can be easily and quickly changed, without the necessity of making any further adjustments to the filler 10.

50 It will thus be seen that the objects set forth above, among those made apparent from the preceding description, are efficiently attained and, since certain changes may be made in the above construction without departing from the scope of the invention, it is intended that all matter contained in the above description or shown in the accompanying drawings shall be interpreted as illustrative and not in a limiting sense.

55 It is also to be understood that the following claims are intended to cover all of the generic and specific features of the invention herein described, and all statements of the scope of the invention, which, as a matter of language, might be said to fall therebetween.

60 Now that the invention has been described, what is claimed as new and desired to be secured by Letters Patent is:

I claim:

65 1. Apparatus for filling cartons with a product comprising at least one cup; a rotatable support therefor; a cutoff gate for 70 controlling filling of said cup; a cutoff gate control member carried by said support; cam means for engaging said cutoff gate control member to open and close said cutoff gate to fill said cup with said product in accordance with the presence and absence of a carton, respectively; and a cutoff plate for 75 retaining said product within said cup, said cutoff plate having

an opening therein for permitting said product to drop from said cup.

2. The apparatus of claim 1, further including a shaft; said rotatable support for said cup being rotatably affixed to said shaft; means supporting said cam means fixedly secured to said shaft and supporting said cam means atop said support for said cup in a position to engage said cutoff gate control member; said cam means comprising a first cam operable to open said cutoff gate and a second cam operable to close said cutoff gate; means coupled to said first and second cams to operate them simultaneously responsive to the presence and absence of a carton to position said first and second cams to cause one of them to be engaged by said cutoff gate control member.

3. The apparatus of claim 1, further including a hopper plate supporting a hopper which is adapted to receive a supply of said product supported atop said rotatable support for said cup; the product within said hopper being delivered atop said rotatable support for said cup for filling said cup in accordance with the operated position of said cutoff gate; and means for imparting a vibratory motion to said support for said cup and said hopper plate.

4. The apparatus of claim 3, wherein said support for said cup and said hopper plate are coupled to one another and wherein said means for imparting a vibratory motion to said support for said cup and said hopper plate comprises a vibrator affixed to said hopper plate.

5. The apparatus of claim 1, further including means for raising and lowering said support for said cup with respect to said cutoff plate; a lower cup support plate supported by said cutoff plate having at least one cup which is slidably and telescopically engaged with said first-mentioned cup; said first-mentioned cup and said cup affixed to said lower cup support plate comprising a volumetric filling mechanism, the volume of which can be changed by raising and lowering said support for said cup with respect to said cutoff plate.

6. The apparatus of claim 1, further including a shaft; said rotatable support for said cup being rotatably affixed to said shaft; a hopper plate supporting a hopper which is adapted to receive a supply of said product fixedly secured to said shaft so as to support said hopper atop said rotatable support for said cup; the product within said hopper being delivered atop said rotatable support for said cup; means supporting said cam means fixedly secured to said shaft and supporting said cam means atop said support for said cup in a position to engage said cutoff gate control member; a lower cup support plate supported by said cutoff plate having at least one cup which is slidably and telescopically engaged with said first-mentioned

cup; said first-mentioned cup and said cup affixed to said lower cup support plate comprising a volumetric filling mechanism; and means for raising and lowering said shaft whereby said support for said cup, said hopper plate and said means supporting said cam means are simultaneously raised and lowered with respect to said cutoff plate and the capacity of said volumetric filling mechanism is accordingly changed.

7. The apparatus of claim 1, further including a lower cup support plate slidably supported atop said cutoff plate, said lower cup support plate having at least one lower cup which is telescopically arranged with said cup supported by said rotatable support, said shaft being vertically adjustable to raise and lower it to thereby telescopically adjust said cup with respect to said lower cup to change the capacity of the product disposable within said cup.

8. The apparatus of claim 7, further including a funnel assembly comprising a funnel support ring releasably and drivingly coupled to said rotatable support for said cup, at least one rigid funnel supported by said funnel support ring below said cutoff plate and in alignment with said cup so that the product dropped from said cup through said opening in said cutoff plate drops into said rigid funnel and a funnel extension associated with each rigid funnel supported in a position such that product dropped into said rigid funnel passes through the latter into said funnel extension, and means for raising and lowering said funnel extensions operated in synchronism with the movement of said carton to lower said funnel extension into a carton to convey said product into said carton to fill it.

9. The apparatus of claim 8, further including a funnel slide bar associated with each rigid funnel, said funnel slide bars being supported by said funnel support ring and each supporting one of said funnel extensions, said means for raising and lowering said funnel extension comprises a cam track supported by said funnel support ring and cam means affixed to each of said funnel extensions and engaged with said cam track, said cam track being formed such that said funnel extensions are raised and lowered by said cam means riding on it as said funnel extensions are rotated.

10. The apparatus of claim 9, wherein said funnel extensions each comprise a fixed funnel portion and a pivotal funnel portion which normally is pivoted to substantially close the end of said funnel extension, means affixed to said pivotal funnel portions operated in synchronism with the lowering of said funnel extensions to pivotally open said pivotal funnel portions, whereby the ends of said funnel extensions are more easily lowered into a carton.
